UNITED STATES PATENT OFFICE.

JOHN F. KELLY, OF PITTSFIELD, MASSACHUSETTS.

MACHINE FOR PERFORATING MUSIC-SHEETS.

1,028,361.

Specification of Letters Patent.

Patented June 4, 1912.

Application filed April 13, 1911. Serial No. 620,735.

To all whom it may concern:

Be it known that I, JOHN F. KELLY, a citizen of the United States of America, residing at Pittsfield, in the county of Berkshire and State of Massachusetts, have invented new and useful Improvements in Machines for Perforating Music-Sheets, of which the following is a specification.

My invention relates to improvements in 10 perforating machines and is designed more particularly as an electrical machine for cutting or perforating a metallic music roll which is then used as an enlarged pattern for the playing rolls of self-playing musical 15 instruments.

The machine is designed for perforating a metallic sheet with holes of the proper length and size, and spaced from each other the desired distance.

20 The invention consists, in general, of a table or carriage that is movable right and left transversely to the line of movement of the roll to be cut and is provided with a series of graduated punches that operate 25 transversely to the line of movement of the metal sheet to be perforated, and a die thereon with which the punches register.

The machine is provided with a note scale 30 representing the notes of a piano and the markings for controlling the expression, over which moves a pointer or index to which a contact brush is attached for controlling the electrical circuits; and a second index pointer is attached to the movable 35 table, this second pointer being adapted to be brought into registration with the first pointer, the brush of which establishes electrical connections through suitable magnetic clutches whereby the table is automatically 40 operated through a predetermined transverse distance when it will come to rest by the circuit being opened. In this position of the table the punching operation takes place in the roll, suitable means being provided for advancing the roll to be cut.

45 The details of construction and operation of my invention will be fully set forth in the specification and drawings forming a part thereof, and specifically pointed out in the 50 claims.

Referring to the drawings,—Figure 1 is a front elevation of the machine showing the reciprocating table, the clutch mechanism

for connecting and disconnecting the source of power by means of which the table is 55 transversely operated, and the index mechanism which determines the number of punches to be operated for making a cutting to represent any particular note. Fig. 2 is a transverse sectional view on the line 60 2—2 of Fig. 1 showing the rack and pinion construction for transversely moving the table in opposite directions, the hand operated ratchet device for advancing the metal ribbon forward in a step-by-step manner, 65 graduated punches, and the clutch for releasing the operating shaft when the punching operation is to be performed. Fig. 3 is a diagrammatic view showing the electrical connections of the machine.

70 Referring to the drawings in detail, *a* designates the transversely reciprocating table which carries the die *b* and the set of graduated punches *c*. The table moves lengthwise of the machine and at right angles to the line of motion of the metal roll to be perforated and is provided with a rack *d* at its lower edge with which meshes a gear *e*, which gear is adapted to be driven in opposite directions by means of two beveled pinions *f* and *g* that are mounted on a shaft *h* and which are operated by means of the magnetic clutches *i* and *j*. The direction of rotation of the gear *e* by means of the pinions *f* and *g* depends upon the energization 80 of either one or the other of the clutches *i* or *j*. The wires *k* and *m* supply the current to the clutches *i* and *j*, and said wires are connected to the two branch terminals *o* and *p* that are insulated from each other 90 by means of the piece of insulation *o'*. These branch terminals *o* and *p* may be placed in electrical connection with the main wire *q* by means of the brush *r* that slides on them, and they are electrically connected to the brush *s* which engages the main wire *q* that is connected to the source 95 of electrical energy *w*.

Attached to the brushes *r* and *s* is the pointer *t* which moves over the note scale *u*, 100 representing the notes of the piano and the markings *u'* for controlling the expression. It will therefore be seen that when the brush *r* engages either one or the other of these branch terminals that the current from 105 the main wire *q* will flow through either

wire *k* or *m* to the magnetic clutches *i* or *j* energizing that particular clutch so as to shift either one of the pinions *f* or *g* into mesh with the gear *e* causing the table *a* to move, for instance, toward the right, if the current flows from the terminal *o* to the clutch *i*.

In order to perforate or cut an opening in the metal roll of the correct length, an index device is shown at *y* provided with figures which indicate and fix the number of punches which are to be brought into action to cut the roll.

The index device raises and lowers the stepped punch selector *z* which is adapted to engage the rack *3* which, in turn, operates the pinion *4* that engages the punching-rod *5* that carries the set of graduated punches *c*.

6 designates an operating shaft that is provided with a worm *7* and with which the teeth of the gear *8* engage. The gear *8* is thrown into and out of action by means of the clutch *9* which is operated by means of the releasing magnet *10* so that when the clutch or pin *9* is retracted, the spring *11* will throw the gear *8* into operation to effect the punching of the metal ribbon, power being transmitted to the gear *8* and shaft *6* by means of the belt *8¹*. The gear *8* is connected to the stepped punch selector *z* by means of the link *12*, whereby motion is transmitted from the shaft *6* to the punching-rod *5*.

It should be observed that the branch terminals *o* and *p* are mounted on a rack *13* which moves with the table *a*, and this rack engages with the pinion *14* on the same shaft of which is secured a pinion *15* that engages the rack *16* of the table *a*. This system of gearing determines the correct ratio between the width of the metal roll that is to be punched and the note scale *u* for the ordinary eighty-eight note piano.

When the operator wishes to punch any particular note, he slides the brush *s* and index pointer *t* to the particular note that appears on the piece of music that is to be reproduced or punched in the master roll.

This causes the brush *r* to engage, say the right-hand terminal *o*, and establishes an electrical connection with the main wire *q* through the brushes *s* and *r* to the right-hand clutch *i* which throws the pinion *g* into mesh with the gear *e* which moves the table *a* toward the right. Movement in this direction will continue until the carriage pointer *17* moves the piece of insulation *o'* into engagement with the brush *r*, thus opening the circuit to the clutch *i* and stopping the movement of the table. Before the punching of the sheet is performed, it is necessary that the exact position of the table be determined.

The preliminary positioning of the table

and the punches carried thereby which has just been described is not always its exact position with relation to the note scale, and in order to bring the table *a* into the exact position and prevent any back lash, its lower edge is provided with teeth *18* with which the teeth *19* on the rod *19¹* mesh. The distance between two of these teeth is equal to the spacing of one note from the other on the note scale. 70

If the preliminary positioning is within half the width of two teeth the locking action must insure precise adjustment of the punches.

The engagement of the teeth *18* with those on the rod *19¹* is effected by means of an electromagnet *20*. 80

The path of the current when the table is in its preliminary position and before the electromagnet *20* is energized is as follows: 85 From the source *w* to the wire *21*, contact piece *22*, arm *23* to the wire *24*, contact piece *25* and its switch *25¹* to the wire *26*, to the make and break device *27*, wire *28* to the main wire *q*, brush *s*, to one of the branch terminals, as *o*, wire *k*, to the clutch *i* back to the other terminal of the source of energy.

After the table has come to rest by reason of the circuit to the clutch *i* being opened 95 when the brush *r* engages the piece of insulation *o'*, the circuit, through the electromagnet *20*, is then closed by the operator moving the contact arm *23* onto the contact plate *29* causing the current to flow from the source of energy and wire *30* through the magnet windings and wire *31* to the common return wire *32*, back to the other terminal of the source of energy. 100

The armature *33* of the electromagnet is 105 attracted and causes the teeth *19* of the rod *19¹* to mesh with the teeth *18* of the table, which armature is held in this attracted position during the punching operation, and in order to maintain this attracted position 110 of the armature, current flows from *w* to the contact-bar *22*, wire *34*, to the make and break device *35* (which is closed after the make and break device *27* is opened,) permitting the current to flow to the wire *36* to the wire *37* through the electromagnet *20* and common return *32* back to the other terminal of the source of energy *w*, it being of course understood that the contacts *27* are not opened until after *35* is 115 closed. 120

When the punching is to be effected, the arm *23* of the foot lever is moved to the contact *38* allowing the current to flow to the wire *39* to the electromagnets *10*, wire *41*, the make and break device *42*, and the common return *32* back to the source of energy *w*. The closing of the circuits through the magnet *10* releases the operating shaft *6* causing the punching-rod *5* to be 125 130

operated through the elements 7, 8, 12, 2, 3, and 4.

The number of punches operating is previously determined by the index *y* which 5 varies the space between the parts 2 and 3.

The gear 8 is provided with the insulating projections 43, 44, and they are so located on this gear that as soon as the punching operations commence the make and 10 break device 27 will be opened and 35 will be closed; and this relation of the make and break devices will continue until the gear 8 has made one revolution, when the projections 43, 44, will have assumed their 15 original position closing the device 27 and opening the device 35. The machine will then come to rest by reason of the operator removing his foot from the foot pedal 45, permitting the contact arm 23 to return to 20 its original position, that is with the graduated punches elevated, as shown in Fig. 2.

After the punching operation, the metal roll (which is shown in Fig. 2 at 46) is fed forward by means of the hand-operated 25 ratchet lever 47, the teeth of which engage the ratchet wheel 48 and cause the ribbon 46 to move forward the desired space corresponding with the time of the music that is being copied, when the operations just 30 described are repeated. The note index *t* is set to effect the cutting of another note.

It will be seen that I have produced a perforating machine for making master rolls that is extremely accurate in its cuttings of 35 the notes, and one that may be operated at considerable speed.

What I claim, is:

1. In a perforating machine, the combination of a carriage transversely movable 40 to the line of motion of the roll to be perforated, punches to effect the perforation, devices to automatically set the carriage in motion and to stop the same when the carriage has reached a predetermined position 45 relative to the width of the roll to be punched.

2. In a machine for perforating master rolls, a carriage, punches, and a die element 50 thereon to effect the perforation of the roll, means to move the carriage transversely to the line of motion of the roll, means to set the carriage in motion in opposite directions, and index means to determine the position of the carriage will come to rest.

3. In a master roll perforating machine, the combination with a movable carriage, 55 electrical terminal branches insulated from each other, an index device, electrical devices for setting the carriage in motion in opposite directions depending upon the position of the index device relative to said branches.

4. In a master roll perforating machine, the combination with a movable carriage, 60 electrical terminal branches insulated from

each other, an index device adapted to move over a note scale, electrical devices for setting the carriage in motion in opposite directions, depending upon the position of the index device relative to said branches, and 70 means on the carriage to register with the index device and the insulation which separates the branches to effect the stopping of the carriage.

5. A master roll perforating machine 75 comprising a carriage operable transversely to the line of motion of the roll to be perforated, a punch and die on the carriage, an index device movable over a note scale, the position of which index device determines 80 the direction the carriage is to be moved prior to the punching operation, and the position in which the carriage will come to rest, and means for effecting the perforation. 85

6. In a perforating machine, the combination of a table movable relative to the roll to be cut, punches and a die on the table, electrical devices to cause the table to move in opposite directions and a definite distance when it will come to rest, including 90 branch terminals insulated from each other, a contact adapted to engage either one of said branch terminals, a source of energy and connections between the same and the 95 contact whereby the direction of motion of the carriage is determined.

7. In a music roll perforating machine, a 100 movable table member, operating means for said member, a main terminal, branch terminals, a contact device having a portion to establish an electrical connection from the main terminal and either one of the branch terminals, an operating device for the table, 105 a device to operate the operating device, and electrical connections therefrom to the branch terminals to cause the table member to follow up the initial position of the current establishing its zero or open circuit contact device to position, a source of electrical energy, and connections therefrom to the main terminal and the branch terminals. 110

8. The combination, in a punching machine, of a main terminal or wire, branch terminals on which a suitable operating tool 115 is carried, means to close the connection to either branch terminal to position the setting of said tool, a source of electrical energy, and connections therefrom to the main terminal and the branch terminals. 120

9. In an electrical perforating machine, a reciprocal table, a main terminal, branch terminals insulated from each other, a contact device for establishing a circuit from the main terminal to either one of said 125 branch terminals, operating devices for the reciprocal table, devices to put the operating devices and the table in motion, electrical connections between the branch terminals and said devices, a source of electrici- 130

cal energy, and a circuit therefrom to the main terminal and the branch terminals.

10. In a perforating machine, a tool support, branch terminals, means to effect the movement of the tool support depending upon the initial position of the support with relation to the branch terminals, a source

of electrical energy, and connections therefrom to the branch terminals.
